UNITED STATES PATENT OFFICE.

VERNON THOMAS LYNCH, OF CHICAGO, ILLINOIS.

HAMMER.

1,139,303.

Specification of Letters Patent.

Patented May 11, 1915.

Application filed January 8, 1915. Serial No. 1,125.

To all whom it may concern:

Be it known that I, VERNON THOMAS LYNCH, a citizen of the United States, and a resident of Chicago, in the county of Cook and State of Illinois, have invented certain new and useful Improvements in Hammers, of which the following is a specification.

My invention relates to means for nailing objects together, such as laths, shingles, siding, etc., to suitable supports, covers on boxes, etc., and one of the main objects thereof is to provide an implement which automatically makes a nail and holds the same in position for driving.

Another object is to provide means for feeding wire for the nails from a coil or the like.

A further object is to provide means for insuring the feeding of the same length of wire for each nail formed and driven.

A further object is to provide means for forming a head of peculiar shape which is best adapted both for driving and for locking engagement with the object into which it is driven; and further objects are to provide a device of this class which is simple in construction and use, entirely automatic in action other than the actual driving, composed of few parts not likely to get out of order or to require repair, and comparatively inexpensive.

My invention is fully described in the following specification, of which the accompanying drawings form a part, in which like reference characters are used to designate like parts in each of the views, and in which:—

Figure 1 is a side elevation of my invention, partly in section, and showing the position of the parts just previous to the formation of the nail; Fig. 2 is a similar view after the nail has been formed and ready for driving; Fig. 3 is a similar view after a nail has been driven and just previous to the feeding of a new length of wire for another nail; Fig. 4 is an enlarged section taken on the line 4—4 of Fig. 1; Fig. 5 is a side elevation of the head, partly in section, with the parts in the position shown in Fig. 1; and Fig. 6 is a section taken on the line 6—6 of Fig. 5.

In the drawings forming a part of this application I have shown a preferred form or embodiment of my invention, comprising

a head 7, a handle 8, a lever 9, and parts 55 connected therewith to be later described, said head having a hammer face 10 at one end thereof and an ax blade 11 at its opposite end, said hammer face being vertically slotted in its forward edge as shown at 12 60 for the reception and guiding of a formed nail ready for driving.

The handle 8 is rigidly secured to the head 7 by means of rivets 13 or equivalent fasteners, and is made of sheet metal of inverted U-shape in cross section, as clearly shown in Fig. 4, a fixed bearing plate 14 being provided intermediate the length thereof against which normally bears a pointed dog 15 through the medium of a leaf spring 16, and I also provide a longitudinally arranged leaf spring 17 at the inner and open side of said handle, secured to a fixed support 18, and having a latch 19 thereon.

Longitudinally slidably within the inner 75 handle end is a shuttle 20, also of U-shaped material, having a slot 21 in each side thereof and through which passes a pin 22 fixed in the handle 8, whereby said shuttle is guided in its movement, a coil spring 23 80 tending to draw said shuttle in the direction of the head 7 when moved from normal position; said shuttle has a shouldered end 24, an inclined plane 25, a fixed pin 26, a fixed bearing plate 27, and a pointed dog 28, 85 normally held against the plate 27 by means of a spring 29, therein and movable therewith and all of which have important functions.

Pivoted at 30, to the lever 9 which is also 90 of U-shaped material, is an arm 31 having a latch 32 on one side thereof and having a coil spring 33 connected therewith, the tendency of which is to draw said arm toward the head 7, thereby always maintaining the outer end of said arm in contact with the floor of the shuttle 20 and, as clearly shown in Fig. 3, the latch 32 on said arm is adapted to engage with the free end of the leaf spring 17 and draw the same toward the lever 9.

As clearly shown in Fig. 5, the head 7 has an inclined bore 34 therethrough for the passage of a wire 35, a forwardly directed lip 36 forming a downwardly and rearwardly inclined recess or flooring 37 at an angle of approximately 30 degrees in the form shown, and a transversely inclined

face 38 adjacent said lip, Fig. 6, and it will be observed that the under side of said lip is also downwardly and rearwardly inclined, this being important as it aids in determining the formation of the head of the nail.

The lever 9 is pivoted to the head 7 at 39 and the sides of said lever project beyond said head in order to furnish supports for a wire cutter block 40 arranged therebetween and riveted thereto, the cutting edge being shown at 41, Fig. 5, and said block 40 is also provided with a nose 42 normally closely adjacent the lip 36, as shown in Figs. 1 and 5, but permitting the wire 35 to pass therebetween; although not shown in detail, the cutting edge 41 of the block 40 is similarly inclined transversely to correspond with the face 38 of the head 7, Fig. 6, and over which it slides in the movement 20 of the lever 9 with respect to the handle 8, and the reason for which is to provide a beveled, and thus substantially pointed, end on the nails.

The wire 35 is fed into the rear of the handle 8 through a slot in the arm 31, Fig. 4, between the bearing plate 27 and dog 28, forwardly between the bearing plate 14 and dog 15, and through the bore 34 in the head 7, and the implement is ready for use. The normal positions of the parts are shown in Fig. 1 and, when the lever 9 is manually drawn toward the handle 8, the cutting edge 41 shears off the portion of wire projecting forwardly of the head 7, and this section of wire may be thrown away as it is not pointed nor of the desired length. In this lever movement toward the handle 8 the arm 31 had engaged the shoulder 24 of the shuttle and forced sail shuttle into the rearward position shown in Fig. 2 until the fixed pin 26 in said shuttle had passed beyond the latch 19 of the leaf spring 17 and been engaged thereby, thus locking said shuttle in rearward position; in this rearward shuttle movement the dog 28 therein had moved along the wire 35 without effect thereon, but the dog 15 had prevented any rearward wire movement and, in the positions of the parts shown in Fig. 2, the wire 50 now extends no farther than the cutting face of the head 7. When the strain on the lever 9 is released the coil spring 33 draws the arm 31 forwardly, thereby forcing the lever and handle apart, and in this arm 55 movement the latch 32 thereon engages the free end of the leaf spring 17 and draws it downwardly, thereby releasing the pin 26 from the latch 19 and the shuttle is released and is instantly drawn forwardly by means 60 of the coil spring 23. In this shuttle movement the dog 28 bites into the wire 35 and carries it along with the shuttle for the full shuttle movement, the dog 15 permitting this forward wire movement, and a length 65 of wire equal to the length of shuttle move-

ment now projects beyond the head 7, as shown in Fig. 1. When the lever is again forced toward the handle this length of wire is cut off as previously described, but in the early stages of lever movement the nose 42 70 had bent this portion of wire downwardly over the lip 36 and thereunder into the position shown in Fig. 2, the shearing off of this portion of wire occurring in the last stage of lever movement toward the handle, 75 and it will be noted that the nail now formed rests in the slot 12 in the hammer face. The implement is now used as an ordinary hammer and the nail driven as far as desired into the wood or other material being nailed, 80 but with only one stroke of the implement; the lever 9 may now be partially released to release the gripping of the nail between the nose 42 and lip 36, and, if the implement is moved a slight distance laterally it is released from the nail; the lever may now be drawn close to the handle and the hammer face used to complete the driving of the nail, 85 after which the lever may be entirely released to feed a new length of wire through 90 the implement, ready for another nail forming operation.

The nose 42 and lip 36 are so shaped as to form the wire into a loop, the inner surface of which is in the axial plane of the nail itself, in other words, the head of the nail curves upwardly and forwardly, upwardly and rearwardly, and downwardly at a desired angle, the intent of which is two-fold, viz:—to provide a hammer striking surface 95 in the axial line of the nail, and to clinch the downwardly inclined end of the head into the material being nailed.

It will thus be seen that I provide an implement which successively and continuously forms nails of a peculiar shape; said implement also holds each nail as formed to enable it to be driven into suitable material, although said nails may be thrown from the implement as soon as formed by the release 105 of the lever without driving into any material; the nails are all of the same shape and length, preserving perfect uniformity; the wire is automatically fed through the implement in desired lengths; the implement 110 may be used with only one hand, leaving the other hand of a workman free to hold or manipulate the work; there are no delicate parts requiring adjustment, or repair; the implement is made almost entirely from 115 stampings; and a highly practical, comparatively inexpensive, implement results which is adapted for many uses.

While I have shown a present preferred combination of specific elements, I do not 125 limit myself thereto, as many changes may be made thereover, within the scope of the following claims, without departing from the spirit of my invention or sacrificing its advantages.

Having fully described my invention, what I claim as new, and desire to secure by Letters Patent, is:—

1. An implement of the class described, comprising a head, a handle, a reciprocating shuttle, means on said shuttle for feeding wire through said head, means for locking said shuttle in one position, means for releasing said locking means, means for moving said shuttle to carry said wire when so released, and means for forming a nail from said wire.

2. An implement of the class described, comprising a head, a handle, means for feed-

ing wire through said handle, a lever, means 15 connected with said head and with said lever for bending a length of wire to form a nail head, comprising a lip on said head and a nose on said lever, and a cutter carried by said lever for detaching a formed nail from 20 the wire.

In testimony whereof I have signed my name to this specification in the presence of two subscribing witnesses.

VERNON THOMAS LYNCH.
